194,704

LIGHTER OR SIMILAR ARTICLE

James Donald Smith, Stroudsburg, Pa., and Seymour Rappoport, Rumson, N.J., assignors to Ronson Corporation, Woodbridge, N.J., a corporation of New Jersey

Original design application Oct. 31, 1960, Ser. No. 62,684.
Divided and this application May 4, 1962, Ser. No. 71,115

Term of patent 14 years

(Cl. D48—27)

FIGS. 1, 2, 3 and 4 respectively are a side elevation and end elevation looking from the left of FIG. 1, and a top plan view of a lighter or similar article embodying our new design, and

FIG. 5 is a perspective view thereof.

This application is a division of application D.62,684, filed October 31, 1960, now Patent D.193,869.

We claim:

The ornamental design for a lighter or similar article, substantially as shown.
